DESIGN FOR A CAN PUNCH

Adolph Henry Albert Mitzlaff, Omaha, Nebr.

Application May 17, 1941, Serial No. 100,992

Term of patent 14 years

To all whom it may concern:

Be it known that I, Adolph Henry Albert Mitzlaff, a citizen of the United States, residing at Omaha, in the county of Douglas and State of Nebraska, have invented a new, original, and ornamental Design for a Can Punch, of which the following is a specification, reference being had to the accompanying drawing, forming part thereof.

I claim:

The ornamental design for a can punch, as shown.

ADOLPH HENRY ALBERT MITZLAFF.
